UNITED STATES PATENT OFFICE

117,593

DESIGN FOR A DOLL

Evelyn L. Menger, Ardmore, Pa.

Application July 22, 1939, Serial No. 86,189

Term of patent 3½ years

To all whom it may concern:

Be it known that I, Evelyn L. Menger, a citizen of the United States, residing at Ardmore, in the county of Montgomery and State of Pennsylvania, have invented a new, original, and ornamental Design for a Doll, of which the following is a specification, reference being had to the accompanying drawing, forming part thereof.

I claim:

The ornamental design for a doll, substantially as shown.

EVELYN L. MENGER.
